Primary Examiner — Mary Shannon Malley*Assistant Examiner* — Michelle Marquart Christeon(74) *Attorney, Agent, or Firm* — Jeenam Park(57) **CLAIM**

The ornamental design for a guard rail for a bed, as shown and described.

DESCRIPTION

FIG. 1 is a rear, right and top perspective view of a guard rail for a bed, showing my new design;

FIG. 2 is a front, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view, showing the article in an in use configuration thereof;

FIG. 10 is an enlarged view thereof, taken from region 10 indicated on FIG. 1; and,

FIG. 11 is another enlarged view thereof, taken from region 11 indicated on FIG. 1.

The long-dash short-dash broken lines in FIGS. 10 and 11 represents the bounds of the enlargement taken from FIG. 1 and forms no part of the claimed design. The dash-dash broken lines illustrate portions of the guard rail for a bed that form no part of the claimed design.

1 Claim, 11 Drawing Sheets(56)
